UNITED STATES PATENT OFFICE.

DENNIS EDGAR GREEN, OF AMARILLO, TEXAS.

GARAGE-DOOR-OPERATING DEVICE.

Application filed August 17, 1926. Serial No. 129,755.

This invention relates to an improved structure which may be referred to as a device for automatically closing and opening garage doors and similar closures.

- 5 Briefly, the invention has reference to a structure of this class which includes gear segments carried by the hinged ends of the doors, rack bars cooperable with these segments, and spring means associated with the 10 rack bars for moving them simultaneously in a manner to swing the doors to closed and open positions, suitable retaining means being provided, and said retaining means being releasable from a distant point by the 15 wheels of the vehicle after leaving and before entering the garage.

The particular features and advantages derived from their special association and arrangement will become apparent from the 20 following description and drawings.

In the accompanying drawings:—

Figure 1 is a side view of a garage provided with a structure constructed in accordance with the present invention,

25 Figure 2 is a detailed plan view of the structure showing the association with the doors and showing the parts in the position assumed when the doors are open,

30 Figure 3 is a similar view showing the parts in another position when the door is closed,

Figure 4 is a similar view showing the parts in still another position when the door is closed,

35 Figure 5 is a similar view showing the doors open,

Figure 6 is a similar view showing the doors closed with the parts in still another position,

40 Figure 7 is an enlarged fragmentary view showing the parts in side elevation,

Figure 8 is a detailed view of a vehicle operated trip device.

45 Figure 9 is a detailed view of a keeper to hold the door either in an open or a closed position.

The device comprises a substantially circular casing 1, which is fastened to the ceiling of the garage 2 as indicated in Figure 50 7 and in dotted lines in Figure 1. This casing constitutes a housing for a coiled spring 3. The bottom wall of the casing is provided with a circular slot 4.

55 Cooperable with this casing are arms 6 and 7 provided with rack teeth 8. The inner

ends of the arms are provided with coupling pins, the arms being connected at their inner ends as at 9 with the portions of the spring represented.

The outer toothed end portions 8 of the 60 arms 6 and 7 are in mesh with teeth of gear segments 10 secured to the hinged ends of the doors 11. Associated with the gear segments and hinge connections are guiding and supporting brackets 12 carrying springs 65 13 for maintaining the teeth 8 in mesh with the teeth 10.

To maintain the doors in closed position I employ a keeper 14. This keeper comprises a tapered block having a seat 15 at 70 its center for reception of the lower edge portion of one of the doors as shown in Figure 2. It is arranged in a recess 16 for sliding movement and is actuated by spring 17. A flexible element 18 is connected to the 75 center thereof and extends through a guide tube 19 which is arranged in the ground just below the surface and extends to a distant point where an operating device is located. This operating device comprises a casing 20 80 embedded in the ground and including a guide receptacle 21 for a wheel operated member 22. This member is actuated upwardly by a spring and it includes a stem 23 extending down into the casing and connected with the adjacent end portion of the cable 18. The depressible member 22 may be of any appropriate portion to aid in permitting the vehicle wheel to pass thereover.

Referring to the operation of the device 90 in view of the above detailed description and assuming the parts to be positioned as shown in Fig. 2 at which time the automobile has been placed in the garage. The person manually closes the doors 11 so that the 95 parts assume the position shown in Fig. 3 thereby tensioning the springs to a certain extent. A cable, chain, or the like 30 is pulled to dispose the parts as shown in Fig. 4, that is, to pass the pivots 9 by the 100 center as shown in Fig. 3 to the position shown in Fig. 4, thereby further tensioning the spring. In the movement from the position shown in Fig. 3 to Fig. 4 the doors will slightly swing inwardly. Therefore the 105 member 14 must be released from engagement with the doors. When it is desired to take the machine from the garage, the doors are opened manually to the position shown in Fig. 5 thereby still further tensioning the 110

spring. Obviously, therefore, when the member 14 which holds the door open is released, the spring will close the doors to the position shown in Fig. 6 and when the member 14 that holds the doors closed is released, the spring will open the doors. Thus in leaving the garage it is only necessary to run the automobile over the trip 22 and when coming in the garage it is only necessary to run over the trip 22 for closing the door in the first instance and opening the door in the second instance.

It is believed that in considering the description in connection with the drawings, a clear understanding of the invention will be had. Therefore, a more lengthy description is thought unnecessary. The present embodiment of the invention has been disclosed in detail merely by way of example since in actual practice it attains the features of advantage enumerated as desirable in the statement of the invention and the foregoing description. It is apparent that changes in the details of construction and in the combination and arrangement of parts may be resorted to without departing from the field of invention hereinafter claimed.

Having thus described my invention what I claim as new is:—

1. In a structure of the class described, in combination, a casing adapted to be secured to a relatively stationary part, said casing being provided in its bottom with a circular slot, a spring arranged in said casing in coiled formation, a pair of arms having pivotal connections at their inner ends with said spring through the slot, a pair of swinging members, gearings between the swinging members and arms.

2. In a structure of the class described, in combination, a casing adapted to be secured to a relatively stationary part, said casing being provided in its bottom with a circular slot, a spring arranged in said casing in coiled formation, a pair of arms having pivotal connections at their inner ends with said spring through the slot, a pair of swinging members, gearings between the swinging members and arms, and a member engaged with one of the arms for assisting in the tensioning of the spring.

In testimony whereof I affix my signature.

DENNIS EDGAR GREEN.
